[57]

ABSTRACT

Improved mouthpiece mounting for a bridle bit including flat, elongated cheek pieces adapted to lie along the opposite cheeks of a horse or like animal and having a mouthpiece disposed transversely therebetween. A pin on each end of the mouthpiece is received within a T-shaped opening on each cheek piece, and rigid U-shaped clips engage the pins within these openings and connect opposite ends of the mouthpiece to the cheek pieces thereby permitting interchange of mouthpieces in the bridle bit. The clips maintain the pins in general alignment with the longitudinal axis of each cheek piece and also permit partial rotation of each cheek piece about the longitudinal axis of each pin. Means are provided for releasably joining the rigid clips to the cheek pieces.

BRIDLE BIT HAVING IMPROVED MOUTHPIECE MOUNTING

This invention relates to bridles, particularly for riding animals such as horses, and is directed specifically to a bridle bit having an improved mouthpiece mounting.

A common bridle for a riding animal such as a horse or pony includes a stall, bridle bit and reins. The usual bridle bit includes a pair of elongated cheek pieces which are held in position along the opposite cheeks of the animal and a mouthpiece which extends transversely between the cheek pieces and is adapted to be received in the horse's mouth. The reins are secured to the lower ends of the cheek pieces and when pulled they cause the cheek pieces to exert a torque force upon the mouthpiece, thereby rotating the mouthpiece in the horse's mouth for exercising control over the horse.

Since animals differ in the force which needs to be applied to exercise the desired control over the animal, it is customary to choose a mouthpiece construction which will produce the desired control with minimum pain or aggravation for the horse. Likewise, certain mouthpieces produce better control over the same horse under different circumstances, for example, a more severe mouthpiece may be used when the circumstances will require quick response of the horse to control signals. Similarly, not infrequently it is desired to employ a specific type of cheek piece, such as a longer cheek piece to help generate the necessary torque upon the mouthpiece with less effort by the rider. Heretofore, the mouthpiece has been mounted to the cheek pieces so that it could not be exchanged without destruction of the mounting, thereby requiring that any interchange of mouthpieces be done in a shop having appropriate facilities. The lack of adequate facilities and expense associated with such interchanges has caused owners to purchase a separate and complete bridle bit for each anticipated combination of cheek pieces and mouthpiece, resulting in large and expensive bridle bit inventories. The problem of inventory has been particularly acute with respect to retail and wholesale harness dealers who have been forced to maintain on hand at least one each of several dozen commercially available combinations of cheek pieces and mouthpieces.

It is therefore an object of the present invention to provide an improved bridle bit wherein the mouthpiece is releasably secured to the cheek pieces of the bridle bit. Other objects and advantages of the invention will appear from the following description and drawings in which:

FIG. 1 is a representation of a bridle bit depicting various features of the improved mounting disclosed herein; and

FIG. 2 is a fragmentary exploded view of the mounting depicted in FIG. 1.

The present invention is illustrated in the Figures. As shown in the illustrations, the usual bridle bit construction includes a mouthpiece 10 disposed transversely between a pair of cheek pieces 12, 14. Each end of the mouthpiece 10 is pivotally secured in an appropriate slot 16, 18 in each cheek piece. As illustrated, this slot is preferably positioned intermediate the top end 20 and bottom end 22 of each cheek piece. The lower ends 22, 22a of the cheek pieces are commonly joined by means of a jaw bar 24 looped at each of its ends into appropriate openings 26, 28 in the lower ends of the cheek pieces to maintain the lower ends of the cheek pieces spaced apart. The length of the jaw bar 24 is approximately equal to the length of the mouthpiece 10 to insure a "square" disposition of the cheek pieces and other construction elements of the bridle. The ends 29, 31 of the bridle rein are also secured in the openings 26, 28 in the cheek pieces 12, 14.

As shown in the Figures, each end of the mouthpiece 10 is provided with pin 30 fitted within a slot 32 in the end of the mouthpiece. This pin 30 extends transversely of the mouthpiece and is received in the bar portion of a T-shaped slot 16 opening outwardly of an edge of the cheek piece 14. The leg portion of the slot 16 accommodates the end of mouthpiece 10. Rigid clip means 36, 38 of generally U-shaped configuration and having openings 40, 42 in each of the legs thereof are fitted over the pin 30 within the slot and secured in position. Heretofore, the clips 36, 38 have been riveted in

position thereby making it completely impractical to exchange mouthpieces except in a properly equipped shop.

Each of the clips 38, 36 is removably secured to the cheek piece by means of a threaded bolt 44, 46, respectively, which 5 is threadably received in internally threaded openings 48, 50 in the cheek piece 14. When the clip means 36, 38 are placed in position to secure the pin 30 of the mouthpiece 10 within slot 16, the openings 40, 42 of the clip 36 are in register with the opening 50, and the openings 35, 37 of the other clip 38 10 are in register with the opening 48 in the cheek piece. Thereupon the clip 36 is secured in position by threading bolt 46 through opening 40, thence through threaded opening 50, thence through opening 42 of the clip 36. The other clip 38 is 15 likewise secured by bolt 44. Preferably, each of the bolts 44, 46 is provided with an enlarged, flattened head 47 having a frictional surface portion 49. Upon either bolt, for example bolt 46, being snugly threaded into its respective threading opening 50, the frictional surface portion 49 thereof contacts 20 the leg 41 of the clip means 36 forcing the leg 41 into contact with the cheek piece 14 whereby clip means 36 is locked against the surface of cheek piece 14 with the leg 41 of the clip 36 performing the function of a locking washer between the head 47 of the bolt 46 and the cheek piece 14. By positioning 25 the flattened head 47 of the bolt 46 on that side of the cheek piece which is to be adjacent the horse, there is no projection which might cause injury to the horse. Slot means 51, 53 is preferably provided in the head of each bolt for receiving a tool such as a screwdriver for facilitating the threading of the 30 bolt into the threaded opening in the cheek piece.

The preferred threaded bolt 46, for example, is of sufficient length to extend fully through the clip 36 to receive a nut 52 threaded thereon, the nut 52, when tightened against the leg 39 of the clip 36 to force the clip into contact with the cheek 35 piece, creating a lock-nut combination with the threaded cheek piece and positively securing the clip in place. Notably, in the absence of this lock-nut arrangement, the vigorous and repeated motion to which the bridle bit is subjected in normal use causes a loosening of the bolt 46 and eventual dislodgment 40 thereof, resulting in a harness failure which can cause the rider to lose control over his mount.

Whereas a description of the manner of mounting only one end of the mouthpiece 10 has been given, it will be understood that the two ends of the mouthpiece are identically mounted 45 to their respective cheek piece. Similarly, each of the several clips are secured in the manner described above for one of the clips.

Because the mouthpiece 10 is releasably held between the cheek pieces 12, 14, the present invention provides a bridle bit 50 wherein an owner can interchange mouthpieces at his leisure or as the circumstances dictate. Accordingly, he needs only to purchase a number of different, and relatively inexpensive, mouthpieces in order to have available a very wide range of 55 bridle combinations. Similarly, a dealer can stock mouthpieces, rather than having to stock many of the more expensive complete bridle bits.

What is claimed is:

1. A bridle bit comprising a pair of generally parallel spaced-apart elongated cheek pieces each having a T-shaped side opening, a mouthpiece disposed transversely between said cheek pieces, pin means disposed adjacent each end of said mouthpiece and extending perpendicularly therefrom on opposite sides thereof, said pin means on one end of said mouth piece being received in the bar portion of said T-shaped side opening of one cheek piece and said pin means on the other end of said mouthpiece being received in the bar portion of said T-shaped side opening of the other cheek piece, one end of said mouthpiece being received in the leg portion of said T-shaped side opening in one cheek piece and the other end of said mouthpiece being received in the leg portion of said T-shaped side opening in the other cheek piece, rigid U-shaped clip means engaging said pin means in their respective side openings and maintaining said pin means 60 aligned generally with the longitudinal axis of said generally 65

parallel cheek pieces while permitting at least partial rotation of each cheek piece about the longitudinal axis of its respective pin means, and means releasably joining said clip means to the respective cheek pieces.

2. The bridle bit of claim 1 including a plurality of said rigid U-shaped clip means each of which includes leg portions having openings therein, and wherein said means releasably joining each of said clip means to said cheek pieces comprises internally threaded openings in each of said cheek pieces adjacent the respective side opening thereof, said openings in said legs of said clip means being in register with one of said openings in said cheek pieces, externally threaded bolt means extending through said in-register openings and threadably engaging said threaded opening in said cheek piece, said bolt means including a relatively enlarged and flattened head having a contact surface frictionally engaging one leg of said clip means when said bolt is threaded in said threaded opening in said cheek piece thereby enhancing the locking of said bolt in its position within said openings, and nut means threaded onto that end of said bolt means opposite said head thereof, said nut means frictionally engaging the other leg of said clip means and forcing said leg into contact with said cheek piece thereby creating a lock-nut arrangement between said nut and said threaded cheek piece and releasably securing said mouthpiece ends to said cheek pieces.

3. In a bridle bit including a pair of cheek pieces and a mouthpiece extending transversely therebetween, the improvement comprising pin means passing transversely through

each end of said mouthpiece and extending perpendicularly therefrom on opposite sides thereof, a T-shaped side opening in each of said cheek pieces for receiving one of said pins which extend from said mouthpiece ends and for receiving one of said mouthpiece ends, rigid U-shaped clip means covering said pin portions in said edge openings, said clip means including leg portions having openings therein, and releasable fastening means for securing the ends of said mouthpieces in the respective side openings of the respective cheek pieces, including internally threaded openings in each of said cheek pieces adjacent the respective side opening thereof, said openings in said legs of said clip means being in register with said openings in said cheek pieces, externally threaded bolt means extending through said in-register openings and threadably engaging said threaded opening in said cheek piece, said bolt means including a relatively enlarged and flattened head having a contact surface frictionally engaging one leg of said clip means when said bolt is threaded in said threaded opening in said cheek piece thereby enhancing the locking of said bolt in its position within said openings, and nut means threaded onto that end of said bolt means opposite said head thereof, said nut means frictionally engaging the other leg of said clip means and forcing said leg into contact with said cheek piece thereby creating a lock-nut arrangement between said nut and said threaded cheek piece and releasably securing said mouthpiece ends to said cheek pieces.
